Inventor.

Charles O. FARRINGTON.

UNITED STATES PATENT OFFICE.

CHAS. O. FARRINGTON, OF BREWER, MAINE.

MACHINE FOR TURNING OR EDGING BRICKS.

Specification of Letters Patent No. 22,790, dated February 1, 1859.

To all whom it may concern:

Be it known that I, CHARLES O. FARRINGTON, of Brewer, in the county of Penobscot and State of Maine, have invented a new and useful Device for Turning or Edging Bricks During the Process of Drying after being Molded; and I do hereby declare that the following is a full, clear, and exact description of the same, reference being had

10 to the annexed drawings, making a part of this specification, in which—

Figure 1, is a side view of my invention. Fig. 2, a longitudinal vertical section of the same, taken in the line x, x , Fig. 3. Fig. 3, 15 a horizontal section in the same, taken in the line y, y , Fig. 1. Fig. 4, a transverse section of the same, taken in the line z, z , Fig. 1.

Similar letters of reference indicate corresponding parts in the several figures.

20 This invention consists in having a series of slats attached by joints or hinges to a suitable frame and connected to a spring, the whole being arranged as hereinafter fully shown and described, whereby the unburned bricks, during the process of drying, may be turned from a flatwise position, as they are left by the molds, to a position edgewise, with far greater facility and rapidity than they can be turned by the 30 usual hand process.

To enable those skilled in the art to fully understand and construct my invention I will proceed to describe it.

A, A, represent two parallel bars of suitable length connected near their ends by traverse bars B, B. To the center of each traverse bar B, an upright C, is attached, and these uprights are connected at their upper ends by a longitudinal bar D, which 40 serves as a handle as will be hereinafter shown.

To the under sides of the bars A, A, slats E, are attached transversely by joints or hinges α . These joints or hinges are formed 45 at the lower ends of pendent plates b, which are attached to the bars A, A, the joints α , being a little below the upper edges of the slats, say about half an inch, the slats being narrower than the thickness of the bricks,

see Figs. 1 and 2. The slats are placed at a 50 suitable distance apart and they are connected at their upper edges by joints α , to a bar F, which is parallel with the bars A, A. To the bar F, one end of a spiral spring G, 55 is attached, the opposite end of said spring being attached to one of the uprights C, and having a tendency to keep the slats E, in a vertical or edgewise position.

The framing of the implement, to wit, the bars A, A, B, B, may be of wood, and also 60 the slats E, the uprights C, C, may be of metal and also the bar F. I do not confine myself however to any particular material in constructing the device.

The implement or device is used as follows: The bricks, shown in red, are discharged from the molds flatwise in the drying yard and in rows, and when the bricks require to be turned on edge, the operator grasps each end of the bar or handle D, and 70 with a foot on each side of the row to be turned. If the bricks are to be turned to the right, the curved end of the bar D, is grasped by the right hand, the other end is 75 grasped by the left hand, the right elbow being outside the right knee. The slats F, are then placed between the bricks, the bars A, A, resting on the tops thereof, and the implement is shoved to the right by the right knee and the slats E, bear against one 80 side of the bricks the latter will be canted or turned upward on their edges, the slats E, turning on the hinges α , so as to follow the inclination of the sides of the bricks as they are turned upward, and thereby prevent the slats from bearing against the edges of the bricks and destroying the sharp angles of the same, see dotted lines Fig. 1. When the bricks are turned on edge and the implement raised therefrom the slats are 90 made to assume their original position by means of the spring G, the implement is again operated as before and a succeeding number of bricks turned.

By this invention twelve bricks may be 95 turned on edge at a single operation, whereas by the usual hand process only two be turned at once.

The device is simple, may be cheaply constructed and will effect a vast saving in labor.

Having thus described my invention what I claim as new and desire to secure by Letters Patent, is,

The slats E, attached by joint hinges *a*, to the bars A, A, and connected by joints *c*,

to the bar F, which has the spring G, attached to it, the whole being arranged substantially as and for the purpose set forth.

CHARLES O. FARRINGTON.
